UNITED STATES PATENT OFFICE

99,969

DESIGN FOR A MATCH BOOK

Louis J. Whitestone, New York, N. Y.

Application February 29, 1936, Serial No. 61,427

Term of patent 7 years

To all whom it may concern:

Be it known that I, Louis J. Whitestone, a citizen of the United States, residing at New York city, in the county of New York and State of New York, have invented a new, original, and ornamental Design for Match Books, of which the following is a specification, reference being had to the accompanying drawing, forming part thereof, in which:

Fig. 1 is a plan view of the match book with the cover partly opened, showing my new design, and

Fig. 2 is a plan view thereof with the cover fully opened.

I claim:

The ornamental design for a match book, as shown and described.

Signed at New York city, in the county of New York and State of New York, April, 1936.

LOUIS J. WHITESTONE.
